UNITED STATES PATENT OFFICE.

MARKUS HOLPFER, OF CORAOPOLIS, PENNSYLVANIA.

SWITCH.

No. 833,524.

Specification of Letters Patent.

Patented Oct. 16, 1906.

Application filed August 8, 1906. Serial No. 829,777.

To all whom it may concern:

Be it known that I, MARKUS HOLPFER, a subject of the Emperor of Austria-Hungary, residing at Coraopolis, in the county of Allegheny and State of Pennsylvania, have invented certain new and useful Improvements in Switches, of which the following is a specification, reference being had therein to the accompanying drawings.

10 This invention relates to certain new and useful improvements in railway-switches; and the invention has for its object to provide novel means whereby a motorman or operator of a car or train can throw a switch 15 without departing from the car or train or causing a cessation in the operation thereof.

My improved switch and switch-throwing mechanism which I employ are particularly designed for street-railways, the cars of said 20 railway being equipped with the switch-throwing device, while the switches are constructed to be easily and quickly thrown by the device. It is obvious, however, that my improved switch and switch-throwing device 25 is applicable to steam-railways by simply equipping a locomotive with my improved device.

The detail construction entering into my invention will be presently described, illustrated, and then specifically pointed out in 30 the appended claims.

Referring to the drawings forming part of this specification, like numerals of reference designate corresponding parts throughout 35 the several views, in which—

Figure 1 is a plan of my improved switch. Fig. 2 is a front elevation of a portion of a car equipped with the switch-throwing device, illustrating the same with relation to a 40 switch. Fig. 3 is a longitudinal sectional view of a shifting bar used in connection with the switch, illustrating an automatic locking device. Fig. 4 is a fragmentary elevation of a car, illustrating a portion of the switch-throwing device. Fig. 5 is a side elevation 45 of a portion of the switch, and Fig. 6 is an elevation of a modified form of bracket used in connection with the switch-throwing device.

50 In the accompanying drawings I have illustrated a switch comprising main rails 1 and 2, siding-rails 3 and 4, the rail 3 having a movable switch-tongue 5, adapted to move with relation to the rail 1 and govern the passage of cars upon the main rails and the siding-rails. The rails are supported upon suit-

able ties or sleepers 6, the tie or sleeper lying under the end of the switch-tongue 5 being provided with plates 7 at each end thereof, upon which a shifting bar 8 is slidably mounted, the bar being connected to the switch-tongue 5, as at 9. This bar is adapted to slide beneath the rails 1 and 2, and in order that it may be moved I bend the ends of said bar upwardly, as at 10. To retain 65 the bar 8 in its shifted position, I employ a locking device comprising a spring 11, which is mounted upon the tie or sleeper 6 between the confronting ends of the plates 7 70 7. The spring 11 is provided with two countersunk portions 12, adapted to engage a depending lug 14, carried by the bar 8. The spring 11 is of a resilient nature and is adapted to recede each time the shifting bar 8 is moved and assume its normal position to lock said 75 bar in its shifted position.

Upon the ends of the plates 7 7 I pivotally mount two horizontal bell-crank levers 15, the confronting ends of said levers being provided with roller-bearings 16 to bear against 80 upwardly-bent ends 10 of the shifting bar 8. The opposite ends of the bell-crank levers 15 are connected by rods 17 to bars 18, pivotally mounted upon the ties or sleepers 6 some distance from the switch-tongue 5. Adjacent to the rails 1, 2, and 4 I mount bearings 19, and in said bearings are pivotally mounted arms 20. Engaging said arms are the slotted ends 21 of the bars 18. The arms 20 are adapted to extend upwardly above 90 the rails constituting the main track and siding and are adapted to be struck by a switch-throwing device carried by the car or train which travels upon the rails.

The switch-throwing device comprises 95 hangers 22, which are carried by the platform 23 of a car. In the hangers 22 is slidably mounted a shaft 24, having rollers 25 journaled upon its ends. The shaft 24 is provided with an outwardly-extending pin 100 26, over which engages the slotted end 27 of an operating-lever 28, said lever being pivotally connected to the platform 23 of the car. Upon the platform 23 is mounted a sector-rack 29, with which the spring-held locking-105 pawl 30 of the operating-lever 28 engages and retains the locking-lever in its adjusted position.

In operation the motorman or operator of the car is adapted to manipulate the lever 28 110 when it is desired to throw the switch-tongue 5. The direction in which the operating-

lever 28 is moved depends entirely upon the direction in which the car is traveling and whether it is desired to continue upon the main track or enter upon the siding-track. Referring to Fig. 1 and assuming that a car is traveling in the direction of the arrow A and it is desired to pass upon the siding-rails 3 and 4, the operating-lever 28 is moved to the left, which throws the shaft 24 to the right, and as the car travels along the main rails 1 and 2 the roller 25 upon the right-hand end of the shaft 24 will strike the arm 20 adjacent to the main rail 2, causing this arm to move forward, and, through the medium of the bar 18, rod 17, and bell-crank lever 15, shift the bar 8 toward the main rail 1, causing the switch-tongue 5 to close. By moving the arm 20 adjacent to the main rail 2 the switch mechanism upon the left side of the rail 1 is moved, but the arm 20 adjacent to the main rail 4 remains in its normal position. Assuming that the train is moving in the direction of the arrow B, the arm 20 adjacent to the rail 1 and upon the forward side of the switch is struck to open the switch-tongue 5 and prevent the car from being derailed. After a car has passed over the switch the switch-tongue 5 can be returned to its normal position by the operator or motorman of the car manipulating the switch-throwing device to strike the arm 20 adjacent to the rail 1 and return the switch-tongue to its normal position. As the arms 20 will be subjected to considerable wear by contacting with the rollers 25, I can use hangers 22', (see Fig. 6,) these hangers being constructed to adjustably hold the shaft 24 to permit of said shaft adjusting itself to the arms 20.

It is thought that the manner of throwing my improved switch will be apparent to those skilled in the art without further description, as the construction is extremely simple and requires no skill on the part of the motorman or operator to throw the switch-tongue.

All of the mechanism subjected to stresses and strains or wearing by constant use is made of strong and durable material, and I desire it to be understood that such changes in the details of construction as are permissible by the appended claims may be resorted to without departing from the spirit and scope of the invention.

What I claim, and desire to secure by Letters Patent, is—

1. In a switch, the combination with main rails, siding-rails, and a switch-tongue, of a shifting bar slidably mounted beneath said rails and having upwardly-bent ends, and connecting with said switch-tongue, a spring mounted beneath said shifting bar and adapted to yieldingly hold said bar in a fixed position, bell-crank levers mounted at the outer ends of said bar, and having roller-bearings

to engage the upwardly-bent ends of said bar, arms pivotally mounted adjacent to said rails and adapted to actuate said bell-crank levers to move said bar, and means to move said arms, substantially as described.

2. In a switch, the combination with rails, a switch-tongue, and a car adapted to travel upon said rails, of a shifting bar slidably mounted beneath said rails and connecting with said switch-tongue, bell-crank levers mounted at the ends of said shifting bar and adapted to engage said bar, arms pivotally mounted adjacent to said rails and adapted to actuate said bell-crank levers, a sliding shaft carried by said car, rollers journaled upon the ends of said shaft and adapted to contact with said arms, an operating-lever carried by said car and adapted to move said shaft, means mounted beneath said shifting bar to yieldingly lock said bar in a fixed position, and means to lock said operating-lever in a fixed position, substantially as described.

3. In a switch, the combination with rails, a switch-tongue, and a car adapted to travel upon said rails, of a shifting bar slidably mounted beneath said rails and connecting with said switch-tongue, bell-crank levers mounted at the ends of said bar and adapted to engage said bar, arms pivotally mounted adjacent to said rails and adapted to actuate said bell-crank levers, means mounted beneath said shifting bar to yieldingly hold said bar in a fixed position, and means carried by said car to engage said arms and shift said switch-tongue, substantially as described.

4. In a switch, the combination with rails, a switch-tongue, and a car adapted to travel upon said rails, of a shifting bar slidably mounted beneath said rails and connecting with said tongue, a shaft slidably mounted beneath said car, rollers journaled upon said shaft, an operating-lever carried by said car and adapted to move said shaft, means mounted adjacent to said rails and adapted to contact with said rollers to shift said switch-tongue, and means mounted beneath said shifting bar to yieldingly hold said tongue in a fixed position, substantially as described.

5. In a switch, the combination with rails, a switch-tongue, and a car, of a shifting bar slidably mounted beneath said rails and connecting with said tongue, arms pivotally mounted adjacent to said rails, means actuated by said arms to move said bar, means mounted beneath said bar to yieldingly hold said bar in a fixed position, and means carried by said car to move said arms, substantially as described.

In testimony whereof I affix my signature in the presence of two witnesses.

MARKUS HOLPFER.
